(57) **CLAIM**

The ornamental design for an adult toy, as shown and described.

DESCRIPTION

FIG. 1 is a perspective view of an adult toy showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the adult toy where the adult toy is in a configuration of use;

FIG. 10 is a perspective view of the adult toy where the adult toy is in another configuration of use;

FIG. 11 is a perspective view of the adult toy where the adult toy is in another configuration of use; and,

FIG. 12 is a perspective view of the adult toy where the adult toy is in another configuration of use.

The additional dash-dash lines shown in FIGS. 9, 10, 11 and 12 are for the purposes of illustrating environmental structure, which form no part of the claimed design.

1 Claim, 12 Drawing Sheets
